ORTHOPEDIC BRACE

Adrian J. Pieterick, Van Nuys, Calif.

Application February 14, 1947, Serial No. 728,478

6 Claims. (Cl. 128—80)

1

The present invention relates to an orthopedic brace, and more particularly to an orthopedic brace for use on a patient who has little or no effective control of one of the major joints of the leg.

In the case of paralysis or injury to a leg which produces loss of proper control of the hip, knee or ankle, for example, it frequently is desirable for the wearer of an orthopedic appliance designed to help correct the condition to be able to lock the joint of the orthopedic appliance which corresponds to the leg joint with which it is associated, and thus permit the wearer of the device to stand relatively at ease, and where some muscular control is retained, to walk without being concerned about the possibility of loss of control of the joint.

Some efforts have been made to provide a releasable lock for orthopedic braces of this character, but many of such devices have been of a nature which are difficult to operate and which would be apt to catch and tear or shear the wearer's clothing, or to pinch and cut his flesh.

An object of the present invention is to make an improved and simplified orthopedic appliance.

Another object is to make a leg brace having an improved releasable locking joint.

Another object is to make a leg brace having a releasable locking joint with the locking parts thereof arranged to minimize danger of catching on the wearer's clothing or flesh.

Another object is to make a leg brace having a releasable locking joint with inconspicuous remote control means which may be operated by a wearer from a normal standing or sitting position.

Another object is to make a leg brace having an upper leg portion adapted to embrace opposite sides of the upper leg of a wearer, a lower leg portion thereof having bifurcated upper ends adapted to embrace opposite sides of a wearer's knee joint, the bifurcations being curved and jointed into a single lower leg portion, with an offset ankle joint portion formed on the lower end of said single lower leg portion.

There is provided in accordance with one feature of the invention, a pair of upper leg brace portions with means for securing them to opposite sides of a wearer's leg, the lower ends of these side portions being formed to connect with a pair of side elements of a lower leg brace portion by means of an articulated joint. The articulated joint has a notched portion with a releasable locking cam arranged for movement into and out of locking position relatively thereto, a

2

locking element being connected to an operative lever flush mounted adjacent the upper end of the device. The articulated lower leg portion has a bifurcated upper end portion terminating in the articulated joints, and having a lower portion thereof offset rearwardly to lie behind the wearer's calf, the lower end of the lower portion being curved around to lie adjacent a side of a wearer's ankle where it is connected pivotally to a footpiece.

These and other objects and advantages of the invention will be set forth more fully in the following description and in the accompanying drawings, of which there are two sheets. In the drawings:

Fig. 1 is a view in side elevation of a leg brace embodying the present invention in connection with an articulated knee joint thereof;

Fig. 2 is a front elevational view of the structure shown in Fig. 1, a lower leg brace portion thereof being broken away to reduce the height of the drawing;

Fig. 3 is an enlarged fragmentary side elevational view of the articulated knee joint portions of the brace, the parts of the brace being shown in knee-straight, locked position in solid lines, and in knee-bent, unlocked position in dot-dash lines;

Fig. 4 is an enlarged fragmentary view in perspective of the upper end portion of a bifurcated side member of a lower leg brace;

Fig. 5 is an enlarged fragmentary view in perspective of a locking lug;

Fig. 6 is a similar view of the lower end portion of one of the upper leg side brace members;

Fig. 7 is a side elevational view of a flush mounted lock-releasing lever;

Fig. 8 is an edge elevational view of the structure shown in Fig. 7, the parts being shown in solid lines in normal locking position, and in dot-dash lines in lock-releasing position;

Fig. 9 is a sectional view taken on the line 9—9 of Fig. 7;

Fig. 10 is a view in perspective of a slide block incorporated in the releasing mechanism shown in Figs. 7 and 8; and

Fig. 11 is a similar view of a side link which forms a connection between the releasing lever and the slide block.

Referring to the details of the structural embodiment illustrated, a pair of upper side brace members 10 and 11 may be of steel, and are secured together by curved connecting bands 12 and 13 which are adapted to pass around the rear of a wearer's leg to hold the brace against for-

ward displacement. Usual padded leather cushions 14 and 15 are provided over these connecting bands, and a leather retaining strap 17 is mounted as a continuation of the leather cushion over the upper connecting band 12. A metal loop 18 is formed to project forwardly from the front edge of each of the upper side brace members near the lower ends thereof, these loops being adapted to receive an upper knee retaining strap 19.

The lower end of each of the upper side brace members is formed, as shown in Fig. 6, with a rearward curved extension 20 thereof having a hole 21 therein adapted to receive a pivot pin 22.

A locking lug 23, shown in detail in Fig. 5, has a rectangular opening 24 therein for slidable mounting on each of the upper side brace members 10 and 11. The lug 23 has a rearwardly extending portion 25 with a pin 27 secured thereto to extend vertically upward therefrom. The upper end of the pin 27 is retained slidably in a guide 28 which is secured to extend rearwardly from each of the side brace members.

The pin 27 has clevis connection with a cable connector 29. The cable connector in turn is swaged onto the end of a flexible wire cable to be described later herein. A coil spring 31 is held in compression between each locking lug 23 and its guide 28, normally to urge the locking lug downwardly to its fullest limit of downward movement.

A lock-releasing lever 32 is mounted pivotally at its upper end between a pair of lugs 33 and 34.

A box enclosure 35 is formed on the outer side of the upper outer brace member 10 below the pivotal mounting for the lever, the enclosure being of a size to receive a block 37 for slidable movement therein. The slide block 37 has a transverse hole 38 therethrough to receive inwardly projecting pins 39 (see Fig. 11) of a pair of operating links 40 and 41 (see Figs. 7, 8 and 11). The upper ends of the links are connected pivotally by screws 42 and 43 to the lever 32.

The side walls of the box enclosure 35 have slotted openings 44 to permit limited movement of the link pins 39 therein. When the lock-releasing lever 32 is swung upwardly to the dot-dash line position illustrated in Fig. 8, the slide block 37 will be moved upwardly within the box enclosure 35.

An opening 45 is provided in the slide block 37, and a pair of notches 45a and 45b are provided in a face of the block extending from the lower end thereof into the opening 45. These notches are adapted to receive control cables 47 and 48 having enlarged head portions 49, the head portions being inserted in the opening 45. Coiled wire sheaths 50 and 51 are mounted to receive the control cables 47 and 48 therein. The cable 47 is connected from the slide block 37 to the outer joint locking pin 27, the enclosing sheath 50 thereof being secured by clamps 52 and 53 screwed to the side brace member 10 in a position so as to be partially covered by the leather pad 15 covering the lower connecting band 13.

The other cable 48 and its sheath 51 extends initially parallel to the cable 47 and is secured in place by the upper cable clamp 52. From here the cable 48 and its sheath 51 are carried around the outside of the connecting band 13 to the inner side of the brace, where the sheath 51 is clamped to the inner upper brace member 11 by a cable clamp 54. This other cable 48 is connected to a pin, similar to the pin 27 in the outer locking lug

23. The lock-releasing lever 32 preferably is provided with a laterally offset extension 55 (see Figs. 1, 7 and 9) to facilitate grasping the handle by the wearer through his clothing.

5 It is understood, of course, that this brace may be worn beneath the trousers or skirt of the wearer, and this arrangement of the lever permits the wearer to manipulate it by grasping the clothing over the lever and then pulling the lever outwardly, carrying the clothing with it, to the limited extent necessary to release the locking lugs 23.

A lower leg brace member, as illustrated, has a bifurcated upper end portion with side portions 57 and 58 adapted to lie on opposite sides of the wearer's knee and to be connected pivotally to the upper brace side members 10 and 11 respectively. The upper end of each of these side portions is divided by a vertical slot 59 adapted to receive the lower end of an upper side brace member 10 or 11 therein, (see Fig. 4) and the rearward sides of these upper end portions are curved, as at 60, to enclose the curved extension 20 on the lower ends of the upper side brace members therein.

The upper end of each of the bifurcated side members 57 and 58 is notched out, as at 61 and 62, to a depth approximately equal to the height of the locking lugs 23. Each of the two side portions 57 and 58 has a hole 63 therein to receive the pivot pin 22. This hole preferably has a bushing 64 of suitable bearing material, such as brass, inserted therein. The pivot pin holes are adapted to align with the holes 21 in the lower ends of the associated upper side members 10 and 11 (see Fig. 6). When so aligned the lower end of the associated upper side member is adapted to engage the bottom of its slot when the brace members are in the full upright or standing position, as illustrated in Fig. 1, so as to permit only rearward bending of the knee joint.

The rear faces 73 of the notches 61 and 62 preferably are made with a slightly rearward slope, and the rear face 74 of the locking lug 23 also preferably is constructed with a similar slope. The locking lug then may be adjusted so that when the parts are in their fully extended locked position, as shown in Figs. 1 and 3, the bottom face 75 of the locking lug will be held with a slight clearance from the horizontal upper faces 76 of the notches 61 and 62 by the engagement of the sloping rear faces 74 of the locking lug and its associated notches. This insures that when the locking lug is at its full limit of downward movement in the notches 61 and 62, under the action of the coil spring 31, the parts will be in a tightly locked position without looseness or wobble movement, and also allows for some wear of the parts without loosening.

The bifurcated upper ends of the lower leg brace member are curved rearwardly and toward each other to pass around the rear of a wearer's calf, and there are joined into a single vertical member 65. The lower end of this vertical member is curved, preferably toward the inner side of the wearer's foot, as at 67, and then downwardly, being pivotally connected at its lower end by a pin 68 to a metal heel piece 69. This heel piece 70 may be elevated, as illustrated in Fig. 1, where the leg to which the brace is fitted is slightly shorter than the other leg, although the height of this heel piece is of course optional with the brace manufacturer.

A leather foot retainer 70 is secured to the heel

piece 69, and the entire foot assembly may be worn inside of an ordinary low shoe.

This lower leg brace is much less conspicuous than previous structures, in which lower leg side pieces are carried down and secured to opposite sides of the wearer's shoe or foot piece.

In putting on the present brace, the upper retaining strap 17 and upper knee strap 19 are loosened, as is also a second knee strap 71 which is connected to a knee retaining pad 72. The wearer's foot is strapped in place by means of the leather foot retainer 70. The upper retaining strap 17 then is drawn up to draw the bands 12 and 13 into proper position against the rear of the wearer's thigh, and the knee straps 19 and 71 are secured in place to draw the brace to a suitable degree of tightness against the wearer's leg. When the wearer straightens his leg to a fully extended position, the locking lug 23 will be moved down into locking position by the coil spring 31, thus locking the leg in straightened position for walking and standing. When the wearer desires to sit or bend the leg, he reaches down and grasps the laterally offset lower end portion 55 of the lock releasing lever 32 through his clothing, and pulls it outwardly sufficiently to raise the locking lugs 23 on both sides of the brace upwardly out of the notches 61 and 62. The leg then may be bent and when thus bent the locking lugs will ride on the curved rear surfaces 60 of the lower leg member, which act as cams to hold the locking lugs in raised releasing position.

When the leg again is straightened, the locking lug will be snapped back into locking position by the action of the spring 31. A valuable feature inherent in the present construction lies in the fact that the lock release is so constructed that it can be operated by a wearer while supporting his weight, as by crutches, and then can use the crutches or other support to lower himself to a seated position.

Extended tests of the brace indicate that there is no possibility that the wearer's clothing or flesh can be pinched or caught by the locking device, since the locking lug never is raised to have substantial clearance from its associated parts, and the parts when released are in sliding contact with each other so that there is no space between them for clothing or flesh to be caught. The same is true of the lock-releasing lever 32, since there are no exposed parts which are apt to pinch or cut the wearer or his clothing.

The drawings and above description relate to the invention as applied to the knee joint of a brace. However, as previously mentioned, the invention also can be applied to the hip and ankle joints of a brace. It is believed that such application would be obvious to an experienced brace maker or designer. However, since the application of the invention as applied to a hip joint is particularly effective, it is desired to point out that when so applied the structure will be substantially the same as that shown in Fig. 3 of the drawings. In such case, however, the numeral 18 would designate a part of the back-brace instead of an upper leg brace portion, and the numeral 57 then would designate an upper leg brace portion. In such case, the release lever may be mounted close to the joint and connected to the locking pin 27 by a short connector of suitable length.

While I have illustrated and described a preferred embodiment of the invention, it will be apparent to those familiar with the art that some changes are possible without departing from the

spirit of the invention. It is desired, therefore, not to limit the invention except as set forth in the following claims.

I claim:

- 5 1. A releasable locking joint structure for an orthopedic brace appliance comprising a pair of upper leg brace members adapted to be mounted on opposite sides of a wearer's leg, a pair of lower leg brace portions each having a vertical fore and aft slot in the upper end thereof and each having a notch on a side thereof adjacent said slot, a cam surface on each lower leg brace portion rearwardly of each of said notches, a lower end portion formed on each upper leg brace member 10 adapted to be inserted in one of said slots, a pivot pin pivotally connecting the inserted lower ends 15 of the upper leg brace members to said lower leg brace portions, fastening means adapted to fasten said appliance to a wearer's leg, a spring pressed locking lug slidably mounted on each upper brace member and adapted to fit into the notches in said lower leg brace portion when the brace is in the knee-straight condition only, thereby locking the appliance in such condition, a vertically extending 20 rod on each locking lug, a guide on each upper brace member slidably to receive said rod, a spring compressed between each locking lug and its guide normally to urge the locking lug toward locking position in said notch, said locking lugs being 25 positioned to ride on the cam surfaces rearwardly of said notches when the locking lugs are raised to released position and the appliance is in knee-bent condition, a lug releasing lever pivotally mounted on an outer side of an upper brace member, a laterally projecting extension carried by 30 said lever and extending beyond the brace member to facilitate grasping through a wearer's clothing, an elongated enclosed guideway adjacent the pivotal mounting of said lever, a slide 35 block slidably mounted in said guideway, link means operatively connecting the slide block to said lever, and a pair of cables connected to said slide block and connected one to each of said locking lugs to raise said locking lugs out of said 40 notches onto said cams for free pivotal movement of the brace members about said pivot pins, and a flexible housing closely encircling each of said cables and secured to said upper brace members to guide said cables in predetermined paths.
- 35 2. A releasable locking joint structure for an orthopedic brace appliance comprising a pair of upper leg brace members adapted to be mounted on opposite sides of a wearer's leg, a pair of lower leg brace portions pivotally connected to the lower 45 ends thereof, a substantially circular joint portion mounted to enclose the joint action and to provide a circular cam adjacent said joint, at least one of the circular joint portions having a notch therein, fastening means adapted to fasten said 50 appliance to a wearer's leg, a locking lug slidably mounted on each upper brace member and adapted to fit into the notch in said circular joint portion when the brace is in knee-straight condition only, thereby locking the appliance in such 55 condition, a vertically extending rod on each locking lug, a guide on each upper brace member slidably to receive said rod, a spring compressed between each locking lug and its guide normally to urge the locking lug toward locking position in 60 said notch, said locking lugs being positioned to ride on the circular cam adjacent said notch when the locking lug is moved to release position and the appliance is in knee-bent condition, a lug releasing lever pivotally mounted on an outer side 65 of an upper brace member, a laterally projecting 70

7
extension carried by said lever and extending beyond the brace member to facilitate grasping through a wearer's clothing, an elongated enclosed guideway adjacent the pivotal mounting of said lever, a slide block slidably mounted in said guideway, link means operatively connecting the slide block to said lever, a pair of cables having countersunk connection to said slide block and connected one to each of said locking lugs to raise said locking lugs out of said notches onto said cams for free pivotal movement of the brace members about said pivot pins, and a flexible housing closely encircling each of said cables and secured to said upper brace members to guide said cables in predetermined paths.

3. A releasable locking joint structure for an orthopedic brace having an upper leg brace portion and a lower leg brace portion pivotally connected to each other, said joint structure comprising a bifurcated end on a first of said brace portions adjacent said joint the outer ends of the bifurcations thereof being flat-surfaced, an endwise extension at an end of the flat end surface of each bifurcation and joining said flat surface at an angle, the other brace member having an end portion inserted between said bifurcations and having a nose portion adapted to have endwise abutting engagement with the first brace portion between the bifurcated end portions to limit pivotal movement in one direction to an aligned condition of the brace portions, a locking lug slidably mounted on the second brace portion and having a flat end portion adapted to overlie the flat ends of said bifurcations and having a surface thereof disposed at an angle to register with the angularly disposed surface on said endwise extension on the first brace portion to secure the leg portions in aligned relation and

10 manually controlled release means mounted to move said lug clear of said endwise extension to free the brace portions for pivotal movement.

4. The arrangement set forth in claim 3, the side of the first brace portion adjacent said extension being curved on an arc substantially concentric with the pivotal axis of the joint, and adapted to provide cam support for the locking lug in other than aligned positions of the brace portions.

15 5. The arrangement set forth in claim 3, the manually operated release means comprising a flush mounted lever, pivoted to one of said brace portions, a sliding block mounted adjacent said lever, a link pivotally connected between the lever and the sliding block to move the block slidably on a pivotal movement of the lever, and a flexible cable connecting the sliding block to the locking lug.

20 6. The arrangement set forth in claim 3, the angle between the extension and the flat end surfaces of the bifurcations being at a slope initially to support the locking lug in spaced relation from said flat end surfaces, thereby to provide for take-up of wear of said extension and the contacting area of the locking lug therewith.
